UNITED STATES PATENT OFFICE

WILLIAM F. OBERHUBER, OF DREXEL HILL, PENNSYLVANIA

METHOD OF MAKING HIGH PRESSURE STEAM JOINTS

Application filed September 30, 1925. Serial No. 59,462.

My invention relates to joints for piping carrying high pressure steam and the like; that is, to pipe joints that are adapted to stay tight under very high fluid pressures within 5 the pipe.

A purpose of my invention is to provide a joint that will automatically tighten with increasing pressure.

A further purpose is to provide a joint 10 well suited to retain fluids having high pressures or subject to widely variant temperatures.

A further purpose is to provide a pipe 15 joint that will take up and stay tight under the longitudinal strains of compression and expansion to which piping is normally subjected under pressure, for example, of steam or oil, and capable of withstanding high pressures.

20 A further purpose is to have a plain-faced flange cooperate with a flange grooved into narrow annular sprung sections.

A further purpose is to give spring to the 25 annular sections by undercutting the annuli or by laterally springing the sections or the material of a diaphragm carrying the annuli.

A further purpose is to provide a dia- 30 phragm between two plain facing flanges, sealing against both flanges by annular spring contacts on the diaphragm, using the lateral spring of the body of the diaphragm or undercutting beneath the annular contacts, to insure good contact and its maintenance.

A further purpose is to have the bearing 35 surfaces of mating high pressure flanges comprise spaced zones with deep grooves in between and to concentrate the contacting pressure between the flanges at the inner rims of the zones by outwardly and rearwardly re- 40 lieving the zones from their inner rims.

A further purpose is to make a flange having spaced zones of bearing surface of resilient material, such as steel, and to undercut the inner rim of each zone, thereby better 45 adapting the zone of contact to accommodate itself to irregularities of a mating flange and to longitudinal strains, increasing its bearing pressure when the fluid pressure within the pipe increases.

50 A further purpose is to provide a dia-

phragm for insertion between mating plain faced pressure flanges with bearing surfaces having spaced zones of contact on each side, undercut at the inner rim of each zone, and each zone relieved somewhat from its inner 55 rim outwardly.

Further purposes will appear in the specification and in the claim.

I have elected to show a few only of the forms in which my invention may be applied 60 but have selected froms that well illustrate the principles involved and which are practical and efficient in operation.

Figures 1 and 2 are side elevations of screw-flange pipe joints applying respectively dif- 65 ferent forms of my invention.

Figure 3 is a longitudinal section illustrating my invention in diaphragm form applied between flanges that are integral with pipe sections.

Figure 3a is a section similar to Figure 3 but showing another application.

Figures 4 and 4a are fragmentary enlarged sections of a portion of a structure seen in Figure 1 and a slight modification thereof, the section being longitudinal with respect to the pipe.

Figures 5, 6 and 7 are transverse sections corresponding generally to line 7—7 of Figure 8 showing different forms of diaphragm 75 for sealing between facing flanges or other surfaces.

Figure 8 is an elevation which may be either front or rear elevation of the dia- 80 phragm whose section is shown in Figure 7. 85

Figures 9 and 9a are enlarged fragmentary sections corresponding to a portion of Figures 7 and 5 but omitting the holding means.

Figure 10 is a fragmentary transverse sec- 90 tion of a pipe and flange to which my invention is applied, the entire flange being integral with the pipe.

Figures 11 and 12 are central vertical sections showing valves to which my invention is 95 applied.

Figure 13 is a front face view of one of the flanges seen in Figure 11 or Figure 12.

Figures 14, 15, 16 and 17 are fragmentary enlarged sections corresponding the first two 100

generally with Figure 11 and the last two generally with Figure 12 but differing 14 from 15 and 16 from 17 in detail.

Figure 18 is a longitudinal section of an 5 expansion fitting connected to pipe by two of my flange joints.

In the drawings like numerals refer to like parts in all figures. Describing in illustration and not in limitation and referring 10 to the drawings:—

It is difficult to maintain the joint of pressure pipe lines tight where the pressure is high, the temperature widely variant or the line subject to bending strain. The increase 15 in pressure of steam and liquids such as oils has increased this difficulty.

My invention is directed primarily to correct this evil, and I have endeavored to build a joint with the following characteristics:—

20 That it uses a standard plain-face flange as one of its members, or, where a gasket is used, two plain-face flanges; that it will accommodate itself automatically to normal irregularities of the standard flange or 25 flanges; that it reduces the requisite strain upon the flange bolts; and that it will accommodate itself and stay tight under "fatigue" lengthening of flange bolts and under the compression and expansion strains 30 normally present in pressure lines or due to temperature changes. Some of my forms also desirably tighten with increase of pressure within the pipe.

In the form shown in Figures 1, 4 and 4a 35 end flanges 10 and 11, which would normally be welded upon adjoining pipe sections 12 and 13, are held pressed tightly together by suitable bolts 14, only a few bolts being shown in the figure.

40 A succession of annular grooves 15 in the bearing surface of one of the flanges 10 divides the face of the flange into a succession of annular teeth 16, 16' and the ends 17, 17' of these teeth afford spaced annular surfaces 45 that support the entire compressive reaction between the flanges.

The surfaces 17, 17' upon the ends of the annular teeth are preferably somewhat relieved or tapered outwardly, that is, cut away 50 somewhat from near the inner rim 18 toward the outer rim 19. This relief outwardly of the ends of the teeth tends to concentrate the entire pressure between the flanges upon annular lines 20 (Figure 4) or narrow zones 55 21 (Figure 4b) at or near the inner rims of the teeth.

Preferably too, the teeth are directed diagonally inward (i. e., the grooves are diagonal so that the teeth are undercut) and are given 60 length and radial thickness such that they yield somewhat in an axial direction of the pipe when the bolts are tightened and to an extent become responsive to fluid pressure within the pipe, an increase in fluid pressure 65 tending to tighten the joint by its tendency

toward straightening out the teeth, thereby increasing the pressure between the teeth and the mating flange.

Obviously the annular teeth may be upon one of the mating flanges, as in Figure 1, 4, 4a, 70 10, 11 and 12, or upon opposite sides of a diaphragm inserted between the flanges, as shown in Figures 2, 3, 5, 6, 7, 8 and 9a.

In Figure 2 the flanges 11' are secured to the pipe sections 12, 13 by threads or welding and are of any standard plain-face type. In Figure 3 the flanges 11² are integral with the pipe and flanges 11³ are loose or are welded to them. The diaphragm 22 is shown inserted between. It seals with each plain flange in 30 the same manner as if the annular edges or surfaces of contact were upon a pipe flange as in Figure 1 and affords the same opportunity for variation of the sealing surfaces, or for axial springing of the teeth if the teeth be undercut, as in any other form.

It will be noted that the innermost tooth circle is undercut in Figures 4 and 4a but is not shown as undercut in Figure 3.

Figure 10 follows Figure 3 in that all of the teeth except the innermost are undercut though in a flange integral with the pipe.

I find some means of providing spring for the teeth to be quite desirable but am not confined in this to the undercutting feature, showing, in Figures 5 and 6 another way of securing this desirable end in order to point out that this feature is in its broader aspects not restricted to any single form.

In Figures 5 and 6 the diaphragms 22', 22² are undercut as in Figures 3, 4 and 4a and may have either edges of tooth contact as in Figure 4 or annular surfaces of tooth contact as in Figure 4a. In all of Figures 5-9a, the innermost tooth is undercut and each of the teeth has spring and also a tendency to tighten more with higher pressure.

In Figures 3, 7 and 9 the diaphragms 22 and 22³ are provided with duplicate surfaces and constructions on opposite sides. Each of the teeth and grooves on one side finds a duplicate of the same diameters on the other. However, this is not true in Figures 5 and 6 which secure a springing action additional to and separate from the springing action due to the undercutting of the teeth through the alternation of the teeth on opposite sides, the grooves and tooth contact portions upon one side lying radially between the grooves and tooth contact portions upon the opposite side so as to use the lateral flexing of the diaphragms as a means of attaining the additional spring or resilience.

The weakening of the diaphragms by grooves from opposite sides assists in this lateral flexing of the diaphragms and may be made to give even a relatively thick diaphragm great flexibility, each of the teeth being compressed axially toward the normal central plane of the diaphragm. The teeth 130

on the same side are compressed toward the normal central plane in the same direction but in the opposite direction from that of the teeth upon the opposite side of each of these 5 diaphragms. Where the teeth are undercut there is a slight tendency under pressure to turn their edges about their anchorages to give them lateral spring in addition to the spring arising from release of compressive 10 strains.

The intensity of pressure of the annuli against the mating flange must be determined with reference to the resilience of the metal and pressure which are to be applied so that 15 there will be no bending or compression of metal beyond the point from which it will fully spring back or expand.

It will be obvious that even in the form shown in Figure 4 where the surfaces at the 20 right taper at each tooth directly from the extreme inner edge of the tooth, there will not be line contact alone but that with compression of the metal of the tooth and of the face with which it contacts and such spring as 25 may take place in radial planes there will be a surface contact with the highest pressure at the tooth edge. In the form shown in Figure 4a, a slight plane surface for contact is deliberately shown but even this would be 30 best if so cut that the contacting surface becomes parallel with the mating flange after any spring of the tooth in radial planes has taken place, and not before.

There are two reasons why the teeth of different annuli may to advantage not all engage the meeting flange equally when the parts are assembled prior to clamping into positon and why they do not require the same extent of pressure or spring resilience 40 against the mating flange when the flanges have been tightened. One of these is purely mechanical, in that the tendency of the flanges to spring makes it expedient to have contact first along the inner parts of the 45 flanges (considered radially) even as a prerequisite to having the teeth equally pressed against the mating flange when the joint is fully tightened. Because I prefer to have each inner annular tooth press more tightly 50 against the flange than the next outer tooth I taper one or both of the flanges slightly away from the other from the inside outwardly or, if the gasket be used, taper the 55 gasket instead of or in addition to the tapering of the flanges, as seen in exaggerated form in Figures 5-9a.

The other reason lies in the successive reductions of pressure effective against the successive teeth and the fact that the outer teeth 60 having less pressure upon them need not be so tightly clamped against the mating flange in order to hold the pressure.

This will be readily understood from the fact that, considering the innermost annulus, 65 there will be so little leakage or tendency to

leakage past the joint formed by it with the mating flange that the pressure within the first annular space 23 will be very much less than that in the pipe. Correspondingly because of the very slight leakage if any past 70 the second annular tooth the pressure in the second space 23' will be less than that within space 23 etc., with the effect that the successive annular teeth will be subjected to progressively lessening fluid pressure. 75

I recognize that the flanges—and the gasket—could be made plane, where the greater pressure is desired or needed upon the outer teeth, securing a good joint but relying chiefly on the outer annulus or annuli. 80

The succession of grooves with intervening contact annuli has been found to be very effective even with bolts which are relatively loose, since any appreciable leakage involves high velocities of flow through and past the successive belts or zones of contact with consequent high friction losses in pressure at these zones and very high shock losses of the character of so-called Carnot-Borda impact losses in each groove. These losses may be roughly measured by the square of the change in velocity in each groove. 85

This is true not only in Figures 1-11, where the pressures to be held are interior, but will be true also in such positions as Figure 12 at 90 the valve face and about the valve seat where the pressure is on the outside and where, correspondingly, the outer annular teeth must take the highest pressure and inner annular teeth receive progressively less pressure as 95 the innermost annular tooth is approached. 100

In all the figures in which the annular teeth are undercut it will be evident that an excessive pressure tends to expand the edge of the teeth into closer contact with the flanges against which they engage. This expansion is thus proportioned to the need and automatically tightens the joint of all the annular teeth to which the pressure is communicated. However, the reduction of pressure from tooth to tooth due to the effectiveness of the joint made by each annular tooth makes the tightening due to pressure upon the other annular teeth rather a reserve than an active force, i. e., it is available in proportion to the pressure present but is ordinarily not applied on account of the low pressure. 105

Where a flat radial contact surface is provided as in Figure 4a I prefer to make it 110 very narrow, securing excellent results with as little as $1/32$ of an inch. The taper of the surface leading up to the contact edge may be very slight, good results having been obtained with as little as $1/100$ of an inch on a distance of $3/16$ of an inch. These dimensions are given for the purpose only of showing one form of the invention from which 115 good results can be obtained but with the knowledge that a great deal of variation is 120 125 130

permissible and without any intention of restricting the invention by the dimensions given.

The spring of the metal and therefore the effectiveness of the joint is affected by the character of metal used for the plain flange but particularly for the annular engaging edge or face. Excellent results have been obtained by use of a high carbon steel or 10 monel metal or alloy steel withstanding high temperature.

In the form shown in Figures 5 and 6, the annular teeth are staggered on opposite sides of the gaskets 22', 22², so that compression 15 of the gaskets between adjoining facing flanges tends to spring the metal of the gasket bodily, sinuously, first toward one axial direction and then in the opposite direction, utilizing the spring of the metal bodily to 20 secure the spring obtained in the other form by the undercutting or in addition to it.

The inner edges 24, 24' are both used and as shown are both undercut. Pressure on the tooth edges 25, 25', tends to bend the disc 25 upon the edges 24' in the direction toward the observer while pressure on the edges 26, 26' tends to bend the disc away from the observer about the edges 25, 25', as a center.

Similarly pressure upon edges 27, 27', 28, 28', 29, 29' and 30 tends to bend the disc about edges 26 or 26', 27 or 27', 28 or 28' and 29 so as in each case to utilize spring of the disc as stated. Of course any anticipated bending of the disc must be allowed for in 35 providing the taper adjacent the edge of each tooth upon the opposite side, cutting sufficiently more taper than would otherwise be required so that the desired taper may remain notwithstanding the bending of the gasket disc. It will be noted that as between 40 Figures 5 and 6 the undercutting of the edges has been reduced in some and eliminated in others of the annular teeth in Figure 5 whereas it is present in full effect in Figure 45 6; also that the gasket in Figure 5 is much thinner than in Figure 6 with the result that the grooves in Figure 5 are more nearly surface grooves whereas in Figure 6 the grooves are relatively deep, sufficiently so as 50 to weaken the metal between any one groove and the next outer groove on the opposite side so as to facilitate bodily bending of the gasket disc of Figure 6 in radial planes.

As will be seen, the tapering of the flanges 55 or/and of the gaskets, where tapering is used, may be made sufficient for the purpose only of securing final equal compression of each of the annular teeth against its facing flange or may be increased to such an amount 60 as to secure a much higher compression progressively of the inner teeth than of the outer tooth or teeth independently of the interior fluid pressure.

Whatever the fact as to this, the resilience 65 of the metal itself to compression, the spring

of the flanges, the spring of the teeth permitted by the undercutting and the bodily spring of the gasket disc in such a form as that of Figures 5 and 6 as well as the expanding force of the fluid within the undercut give 70 an extremely strong and resilient pressure between the faces of the annuli and the flanges and cause the annuli to maintain contact and high pressure against the flanges even where fatigue of the bolts has caused 75 them to slack slightly in their hold.

Because of the resilience of the joint the bolts need not have the same tension as in other joints, greatly reducing and nearly eliminating fatigue lengthening of the bolts. 80

In Figures 7 and 8 are shown attachment lugs 31 threaded or otherwise arranged for engagement by outside means so that each disc can be supported by means of the lug to place the disc and maintain it in proper alignment during the assemblage of the joint and until the disc is fitted tightly enough between the flanges to need no further 85 steadyng or support.

In Figure 3a I have shown a gasket disc 89 such as in Figures 5-7 used for the combined purposes of sealing between the pipe and flange and of sealing against the flange, in order to insure the tightness of the entire joint. It is applicable to any form in which the pipe end is faced in proper position for engagement.

Unlike the pipe 12 which is threaded and welded into the flange in Figure 1, pipe 12' which is welded and peened into the flange in Figure 2, but both of which terminate short of the end of the flange, and the pipe 12² which is turned over to form the facing flange 11² in Figure 3, the pipe 12³ in Figure 3a is threaded into the flange and welded 105 there but extends to the face of the flange and is faced off in line with the plane or slightly relieved face of the flange 10⁴ so that the inner teeth 24 and 24' of the disc gasket engage with the faced ends of the pipe and seal 110 fully against them.

In addition to this seal forming one of the series of sealing contacts of the gasket against the flange considered in its entirety, effective as in the other figures for this purpose, it forms a protective seal for the end of the pipe in its joint with the flange itself, protecting fully to the extent of its effectiveness, and, so far as there may be any leakage, greatly reducing the pressure in the zone between the pipe and the next tooth 25'. This reduced pressure is much less likely to leak past the threaded and welded joint between the flange and pipe than is the pressure interior to the pipe.

In Figures 11 to 17, inclusive, my invention is applied to valves for the purpose of showing the applicability of the invention to flanges generally including the face flanges of valves and the flanges of valve seats; also 130

to temporary joints such as valves for which latter purposes separate application for patent will be made.

The valves 32, 32' are provided with face flanges 33, 34, 33', 34' having annular teeth and intervening grooves corresponding to those shown in Figures 4 and 4a. On the other hand flanges 35 are plane or slightly tapered for the purpose already indicated. 10 These flanges are all adapted to engage with other flanges as in the structures of Figure 1. However, the flanges 36 upon the valve seat 37' in Figure 13 differ in that the pressure is applied in Figure 11 upon the opposite side 15 of the seat from that to which it is applied in Figure 12 resulting in a difference in direction in the slope of the teeth in the two figures. The teeth and grooves in Figure 11 slope toward the engaging surface and inwardly as in Figure 1, whereas those in Figure 12 slope toward the engaging face and outwardly because the steam pressure is applied to the outside of the seat.

Each of these valve seats is provided with 25 interior engaging projections for spanner wrench use in placing the seat and is threaded at 38 to engage the threads of valve web or flange 39. By means of these threads the annular teeth 16, 16', 16'', 16''' (Figures 14-17) 30 are forced firmly against the surface 40 of the flange making possible the same character of engagement with the same advantages of tapering one or both surfaces to make tighter engagement along the inner contacts 35 in Figure 11 or the outer contacts in Figure 12 as in the other constructions.

The valves 41, 41' in these two figures 12 and 13 are also provided with annular teeth which may be of any of the types indicated, 40 which teeth engage the faces or seats 42 to close the valves. As in the case of the seal for the valve seats in the two Figures 11 and 12 the teeth and grooves are reversed in their slope in Figure 12 as compared with the slopes in Figure 11, because of the fact that the pressure is from the outside in Figure 12 instead of from the inside as in Figure 11 and in the other figures.

I have shown the valve operating means 50 conventionally by stems 43 operated by any mechanism not shown.

The application to the gate valve is not intended to restrict the utility to this form of valve nor, indeed, to valves as this invention 55 has utility in the seals between valves and their seats and between the seats and their supporting structure in many types of valve as well as in other places in which it is desired to seal between a flange and its support.

Cutting the grooves within a pipe flange so 60 as to utilize one of the pipe flanges to carry the annular contact teeth reduces the leakage surface to a single plane or approximate plane between two flanges, offering an advantage 65 from this standpoint which is not found where

a gasket is used and contacts must be formed on opposite sides of the gasket, giving two planes or approximate planes of contact. However, this is more than made up for most uses in the gasket form by the reduction in 70 volume of high grade metal which must be supplied and handled making it possible to use a relatively thin disc of suitable metal instead of making the entire flange or pipe of such material. The machining is greatly facilitated and the disc only need be supplied. 75

It will be evident that the progressive pressures of different spaced annuli against facing flanges may be of advantage in all of the forms illustrated by me whether between 80 facing flanges or between facing plain flanges and an intervening gasket or in a flange seat or rim such as the valve seat shown or in the engagement between the valve and its seat, but that my invention is of great value also 85 where the pressures are equal or the faces within planes.

It will be evident moreover, that the so-called "plain" faces or flanges need not be "plane" even where differential pressures are sought or relative tapers are desired, provided the cooperating member is correspondingly changed in shape to cooperate with it; and that the progressive differences in pressures of the annuli against the flanges 90 are advantageous even when there are only three such annuli as in the illustration—though there is no such restriction in fact—of the valve seat contacts and the valve contacts of Figures 11 and 12. 95

In thin gasket form I have secured excellent results without undercutting; also by sloping the teeth in radial planes directly from the extreme edge of the tooth or from a point just back of the edge to the bottom 100 of the groove giving a very much steeper slope to the axially directed outer "face" of the tooth than in the example cited. I have found vanadium steel, nickel steel and chrome-nickel steel among other alloy steels 105 give a resilience and stand up under the temperatures corresponding to high pressures and superheats in a way well suited to this duty. Carbon steel, Monel metal and all of these are also well suited for 110 use with oils and other liquids at high as well as at low pressures, and under wide differences in temperature.

I consider the sharp tooth edge and the 115 resilience of pressure quite important in my invention. With these features the annular teeth of my joint, need not be compressed to the limit of their permissible compression and yet will permit some slackening and still hold. In such a location as seen in 120 Figure 18, for example, they will permit slight rocking of the flanges due to expansion and contraction of the straight pipe sections without leakage and, in general, in 125 all locations will stand up under longitu- 130

dinal, diagonal and lateral strains to a remarkable extent.

By maintaining a balance of compression such that the joint will stand additional compression on one flange side with or without release of part of the compression across the flange at the opposite side without exceeding the compressive limit upon the part additionally compressed nor losing compression too much to maintain tightness of joint where the compression is somewhat slackened, I secure substantially fool-proof conditions as against lateral strains to the system and rocking or diagonal strain upon the joint, at the same time protecting against such slackening as takes place by reason of fatigue of the bolts. In reliability and permanence my joints are quite comparable with welded joints at the same time that replacements and repairs involve cost, time and trouble insignificant as compared with these items for welded joints.

Undercutting as herein used is intended to refer to cutting beneath the surface so as to leave an axially overhanging ledge which will tend to bend in a radial direction in response to axial pressure.

Attention is directed to the fact that the surface undercut need not make contact along a line only but may make contact along a narrow annulus instead of with greatest pressure along a line and reducing pressure over the remainder of an annulus of ultimate contact.

It will be obvious that in view of my disclosure herein a large part or all of the benefit of my invention may be secured by those skilled in the art by constructions and methods which are not copied from mine but which contain the same inventive concept. It is my purpose, therefore, to include herein all such modifications and changes as come within the reasonable spirit and scope of my claims.

Having thus described my invention, what I claim as new and desire to secure by Letters Patent is:—

The method of giving resilience to a solid metallic gasket which consists in providing narrow spaced annular surfaces engaging with facing flanges on opposite sides of it, in placing the annular contacts at different distances from the axis on one side of the gasket as compared with those on the opposite side thereof to spring the gasket and undercutting the surfaces.

WILLIAM F. OBERHUBER.
